CLAIM

The ornamental design for an automation gateway, as shown and described.

DESCRIPTION

FIG. 1 is a top, front, right side perspective view of an automation gateway showing our new design with features illustrated in broken lines for illustrative purposes and thus not constituting a part of the claimed design;

FIG. 2 is a right side, top, front perspective view of the automation gateway of FIG. 1;

FIG. 3 is a back, top, right side elevational view of the automation gateway of FIG. 1;

FIG. 4 is a back, right side, top elevational view of the automation gateway of FIG. 1;

FIG. 5 is a bottom, front, right side perspective view of the automation gateway of FIG. 1;

FIG. 6 is a right side elevational view of the automation gateway of FIG. 1;

FIG. 7 is a left side elevational view of the automation gateway of FIG. 1;

FIG. 8 is a front elevational view of the automation gateway of FIG. 1;

FIG. 9 is a back elevational view of the automation gateway of FIG. 1;

FIG. 10 is a top plan view of the automation gateway of FIG. 1; and,

FIG. 11 is a bottom plan view of the automation gateway of FIG. 1.

The dash-dot broken lines immediately adjacent to the shaded surfaces define the boundary of the claim, which extends to the boundary but does not include the boundary; while all other broken lines in the drawings depict portions of the automation gateway that form no part of the claimed design.
